United States Patent Office

Des. 214,878

Patented Aug. 12, 1969

214,878

DISPLAY BOX FOR WATCH BANDS OR THE LIKE

Yuen Sang Poon, Hong Kong, assignor to Baldwin Bracelet Corporation, New York, N.Y., a corporation of New York

Filed May 15, 1968, Ser. No. 11,943

Term of patent 14 years

Int. Cl. D9—04

U.S. Cl. D9—185

FIG. 1.

FIG. 2.

FIG. 3.

FIG. 4.

FIG. 5.

FIG. 6.

FIG. 7.

FIG. 1 is a front perspective view of the display box, showing my new design;

FIG. 2 is a left side view thereof;

FIG. 3 is a right side view thereof;

FIG. 4 is a top plan view thereof;

FIG. 5 is a bottom plan view thereof;

FIG. 6 is a front elevational view thereof; and

FIG. 7 is a rear elevational view thereof.

I claim:

The ornamental design for a display box for watch bands or the like, substantially as shown.
